US00D545164S

(12) **United States Design Patent** (10) **Patent No.:** **US D545,164 S**
(45) **Date of Patent:** **** Jun. 26, 2007**

(54) **WALLPAPER CUTTER**

(75) Inventor: **Israel Holby**, Fayetteville, AR (US)

(73) Assignee: **Marshalltown Company**,
Marshalltown, IA (US)

(**) Term: **14 Years**

(21) Appl. No.: **29/244,610**

(22) Filed: **Dec. 12, 2005**

(51) **LOC (8) Cl.** **08-03**

(52) **U.S. Cl.** **D8/98**

(58) **Field of Classification Search** D6/14,
D6/98; 30/280, 294, 162, 320, 314, 315
See application file for complete search history.
